[57] CLAIM

The ornamental design for mirrored handle for closet doors or the like, substantially as shown and described.

DESCRIPTION

FIG. 1 is a front perspective view of a mirrored handle for closet doors or the like, showing my new design;
FIG. 2 is a rear perspective view thereof;
FIG. 3 is a front elevational view thereof;
FIG. 4 is a top plan view thereof, the bottom plan being a mirror image thereto;
FIG. 5 is a side elevational view taken from the left of FIG. 1;
FIG. 6 is a side elevational view taken from the right of FIG. 1.
